CLAIM

The ornamental design for an electric connector, as shown and described.

DESCRIPTION

FIG. 1 is a front elevation view of an electric connector, showing our new design;
FIG. 2 is a top plan view thereof;
FIG. 3 is a bottom plan view thereof;
FIG. 4 is a side view thereof;
FIG. 5 is a rear elevation view thereof;
FIG. 6 is a 1st perspective view thereof; and,
FIG. 7 is a 2nd perspective view thereof.
The shading in the figures shows contour and not surface ornamentation.
